UNITED STATES PATENT OFFICE

2,030,941

ELECTRIC CONTROL APPARATUS FOR
FUEL BURNERS

Abraham L. Rubel, Des Moines, Iowa, assignor to
Penn Electric Switch Co., Des Moines, Iowa, a
corporation of Iowa

Original application August 15, 1932, Serial No.
628,883. Divided and this application Decem-
ber 31, 1934, Serial No. 759,964

2 Claims. (Cl. 158—28)

An object of my present invention is to provide control apparatus for the electric circuit of a fuel burner, the apparatus being comparatively simple and inexpensive to manufacture.

The present application is a division of my co-pending application, Serial No. 628,883, filed August 15, 1932, this application disclosing a "purging" type of circuit, while the parent application has been restricted to a "lock-out" type of circuit.

10 A further object is to provide control apparatus including a warp switch which is energized after combustion occurs in order to break the circuit through the heater of a safety switch, so that upon combustion occurring and being maintained, the safety switch will not trip out.

Still a further object is to provide a control for the burner so arranged that upon combustion failure a purging period is provided by the slow cooling down of a warp switch and contacts of the warp switch are re-engaged after such cooling down so that the control apparatus is re-cycled for further automatic operation.

20 Still a further object is to provide control apparatus including a relay which initiates and terminates operation of a fuel burner and which initiates operation of ignition mechanism for the fuel burner, termination of the operation of the ignition mechanism being effected by combustion occurring.

30 Still a further object is to provide a control apparatus in which a safety switch heater, a warp switch and a relay are all in circuit with each other, a combustion responsive switch being effective to close the heater for the warp switch, which upon becoming heated will open the circuit through the safety switch heater so that upon combustion failure the warp switch heater will be de-energized and, after slowly cooling down, the warp switch will close for re-initiating operation of the burner, the delay period of time during which the warp switch heater cools down being of such length as to provide a purging period for the burner. The apparatus is used on a fuel burner so that upon combustion failure occurring, such as caused by a down draft in the furnace, a slug of water in the fuel oil or the like, automatic operation of the apparatus will recycle the burner after a purging period has been provided to allow the draft of the furnace to purge the combustion chamber of any exposed gases caused by the introduction of fuel after combustion fails.

With these and other objects in view my invention consists in the construction, arrangement

and combination of the various parts of my device, whereby the objects contemplated are attained, as hereinafter more fully set forth, pointed out in my claims, and illustrated in the accompanying drawing, in which:

5

Figure 1 is an electrical diagrammatic view showing the circuit for my purging type of control apparatus for fuel burners.

Figure 2 is a simplified diagrammatic view provided to facilitate tracing the various circuits 10 through the elements of the apparatus.

15 On the accompanying drawing I have used the reference numeral 10 to indicate a line switch. A limit switch is shown at 12, which may be temperature or steam pressure operated and which is ordinarily used in control circuits of furnaces and boilers to prevent the furnace or boiler being heated to an excessive degree. Junction boxes are shown at 14 and 16. These form no essential part of my present invention, but are merely provided for the convenience of the electrician when installing or wiring the apparatus. The junction box 16 has terminals indicated at 1, 2, 3 and 4.

20 My apparatus further includes a room thermostat 18, a combustion responsive control switch 25 20, an ignition switch 22, also responsive to combustion, a safety switch 24, a warp switch 26 and a relay 28. The relay 28 includes an armature 28a to be attracted by energization of the relay. At 30 a furnace is shown and the burner 30 therefor is shown more or less diagrammatically at 32.

25 An ignition transformer is shown at 34 and a spark gap at 36. This comprises the ignition mechanism mentioned in some of my claims.

35

The control switch 20 has contacts 38, 41 and 42. The contacts 38 and 41 may be termed "first contacts closed in the presence of combustion" while the contacts 38 and 42 may be termed "second contacts closed in the presence of combus- 40 tion". The ignition switch 22 has contacts 44 and 46 closed in the absence of combustion.

45 The safety switch 24 has contacts 48 and 50. The safety switch includes a heater 52 and a bi-metal latch 54 which when warped to the dotted line position of Figure 1 by heat from the heater 52 will permit disengagement of the contacts 48 and 50. The warp switch 26 includes contacts 56 and 60 and a bi-metal actuator 62 for the contacts 56. A heater 64 is provided for warping the bi-metal actuator 62 to open the contacts 56 and 60 when the bi-metal element 62 warps due to the action of the heater 64.

50 The relay 28 has burner control contacts 66 and 68 and holding contacts 70 and 72. The con-

trol and ignition switches 20 and 22 are normally in the solid line positions. Upon combustion occurring, a bi-metal helix 21 causes movement of the contacts 38 and 46 to their dotted line positions. The combustion responsive switches 20 and 22 are of the ordinary type commonly termed a "stackswitch" having a slip connection to cause immediate movement of the movable contacts from one position to another and thereafter permit slippage.

10 The warp switch 26 when heated by energization of the heater 64 warps to the dotted line position of Figure 1. In conjunction with my apparatus, I provide a transformer 74 having 15 a primary winding 76 and a secondary low voltage winding 78 so that the relay mechanism for controlling it need not be constructed for high voltage current.

Practical operation

20 Closing of the contacts in the room thermostat 18 will establish a first circuit (indicated as "1st" on the drawing) through the safety switch heater 52. The contacts 56 and 60 of the warp switch 26, the relay 28 will return to the secondary 78 of the transformer 74. This initiates operation of the burner and of the ignition mechanism by closing the contacts 66 and 68. The operation of the ignition mechanism is terminated through separation of the contacts 44 and 46 caused by the presence of combustion.

25 Upon combustion establishment, the contact 38 engages the contact 42 for establishing a "2nd" circuit through the warp switch heater 64 to cause the warp switch to warp to its dotted line position. This opens the circuit through the safety switch heater 52.

30 Combustion establishment also closes the circuit through contacts 38 and 41 to establish a "3rd" or holding circuit through the contacts 10 and 72 of the relay which have been engaged by energization of the relay.

35 Upon combustion failure the contact 38 separates from the contacts 41 and 42, thus de-energizing the warp switch heater 64 and de-energizing the holding or 3rd circuit through the contacts 70 and 72 for terminating operation of the burner 32 by separation of the contacts 66 and 68. Thereafter the heater 64 will gradually cool down and so will the bi-metal element 62 of the warp switch 26. It will finally assume a position re-engaging the contacts 56 and 60 which re-establish the 1st circuit through the relay coil to re-cycle the apparatus by re-initiating operation of the burner 32. The period of time during 40 which the bi-metal element 62 moves from the dotted line position to the full line position of Figure 1 provides a period during which the furnace is purged of gases which might explode when the contacts 66 and 68 are re-engaged to re-establish ignition as well as re-initiate operation of the burner.

45 The warp switch operates the safety switch heater circuit and controls the main circuit so that a purging period may be provided after which the operation of the burner is re-initiated and the heater 52 of the safety switch is energized so as to guard against combustion not occurring by opening the main circuit after a period of time sufficient to permit combustion to occur if the controller is in proper condition for operation. If there is any condition present which will not allow combustion to occur, then the contacts 48 and 50 are separated after the time period mentioned, whereupon the trouble must be remedied

5 and the safety switch thereafter reset manually for again placing the burner in operation.

Although I have shown the transformer 74 it will be obvious that my apparatus may be operated by high voltage current and the transformer omitted. A change of this character and others may be made in the construction and arrangement of the parts of my device without departing from the real spirit and purpose of my invention, and it is my intention to cover by my 10 claims any modified forms of structure or use of mechanical equivalents which may be reasonably included within their scope.

I claim as my invention:

1. In combination with an electrically operated 15 fuel burner, a control system comprising a relay having an actuating winding, a holding winding and holding contacts operable when the actuating winding is energized to close the burner circuit to initiate operation, a room thermostat controlling energization of said relay, a thermal time limit cut out switch controlling said system and including a resistance heater, a warp switch having a warp element, a heater and contacts which are closed when said element is cold and open 20 when said element is heated, combustion responsive means having first and second contacts closed in the presence of combustion, a first circuit including in series said room thermostat, said cut out switch heater, said contacts of said warp switch and said actuating winding, a second circuit shunting said cut out switch heater, said contacts of said warp switch and said relay and including in series the first contacts of said combustion switching means and the heater for 25 said warp element and a third circuit in parallel with the heater for said warp element and including in series said second contacts of the combustion responsive switching means, said holding contacts and said holding winding, said warp element moving slowly when cooling due to de-energization of its heater caused by combustion failure opening said first set of contacts of said combustion switching means whereby a purging period is provided between the de-energization 30 of said relay caused by combustion failure opening said second contacts of said combustion switch to stop operation of said burner and re-engagement of the contacts of said warp switch to re-initiate operation of the burner by re-establishing said first circuit.

35 2. In combination with an electrically operated fuel burner and its ignition mechanism, a control system comprising a relay having an actuating winding, a holding winding and holding contacts operable when the actuating winding is energized to close the burner circuit to initiate operation, a room thermostat controlling energization of said relay, a thermal time limit cutout switch controlling said system and including a resistance heater, a warp switch having a warp element, a heater and contacts which are closed when said element is cold and open when said element is heated, combustion responsive means having first and second contacts closed in the presence of combustion and third contacts opened in the presence of combustion and connected in series with said ignition mechanism, a first circuit including in series said room thermostat, said cut out switch heater, said contacts of said warp switch and said actuating winding, a second circuit shunting said cutout switch heater, said contacts of said warp switch and said relay and including in series the first contacts of said combustion switching means and the heater

for said warp element and a third circuit in parallel with the heater for said warp element and including in series said second contacts of the combustion responsive switching means, said holding contacts and said holding winding, said warp element moving slowly when cooling due to de-energization of its heater caused by combustion failure opening said first set of contacts of said combustion switching means whereby a

purging period is provided between the de-energization of said relay caused by combustion failure opening said second contacts of said combustion switch to stop operation of said burner and re-engagement of the contacts of said warp switch to re-initiate operation of the burner by re-establishing said first circuit. 5
